UNITED STATES PATENT OFFICE.

FRANK HEATH, OF NATIONAL CITY, CALIFORNIA.

SARDINE-TURNING APPARATUS.

Application filed February 2, 1922. Serial No. 533,573.

To all whom it may concern:

Be it known that I, FRANK HEATH, a citizen of the United States, residing at National City, in the county of San Diego and

5 State of California, have invented a certain new and useful Improvement in Sardine-Turning Apparatus, of which the following is a specification.

My invention relates to an apparatus for 10 turning sardines so that they move head foremost and turn on their backs and the objects of my invention are: first, to provide an apparatus of this class to take the sardines from a tank or other receptacle 15 and turn them into chutes so that they all move head foremost; second, to provide such an apparatus in combination with a means for turning said sardines on their backs; third, to provide an apparatus of 20 this class which receives the mass of sardines moving in different directions and turns them all in one direction; fourth, to provide an apparatus of this class which which tends to hold and move the sardines in 25 their course head foremost and fifth, to provide an apparatus of this class which is very simple and economical of construction, durable, easy to install, which is automatic and positive in its action and which will 30 not readily deteriorate or get out of order.

With these and other objects in view as will appear hereinafter my invention consists of certain novel features of construction, combination and arrangement of parts 35 and portions as will be hereinafter described in detail and particularly set forth in the appended claims reference being had to the accompanying drawings and to the characters of reference thereon which form 40 a part of this application in which:

Figure 1 is a front elevational view of a series of units of my apparatus partly broken away and in section to facilitate the illustration; Fig. 2 is a plan view thereof, 45 parts broken away to facilitate the illustration; Fig. 3 is a sectional elevational view taken through 3-3 of Fig. 1; and Fig. 4 is a transverse sectional view of a slightly modified form of my apparatus.

50 Similar characters of reference refer to similar parts and portions throughout the several views of the drawings.

The conveyer 1, drum 2, shaft brackets 3, pulley 4, chutes 5 and 6, sliding members 55 7, brushes 8, guide members 9, guide supports 10, tie bars 11, connecting bars 12,

crank shaft 13, shaft brackets 14, pulley 15, chutes 16 and 17 and guard 18 constitute the principal parts and portions of my structure.

60 The belt conveyer 1 is mounted on a drum 2 which is fixed to the shaft 2^a. Said belt conveyer is provided with cleats 1^a adapted to receive the sardines from a tank or hopper, not shown on the drawings, and carry 65 the same over said conveyers onto the chutes 5 and 6. Said shaft 2^a is revolvably mounted in the shaft bracket 3 and is driven by the pulley 4. These chutes 5 and 6 are positioned in rows in staggered spaced relation 70 as shown and the extended ends of said chutes 5 and 6 communicate with brushes 8 secured to two sets of sliding members 7 above and below. Said brushes are preferably made of metallic blades or other mate- 75 rial of suitable stiffness and secured in block 8^a perpendicular with the direction of motion of said sliding members. Said brushes are inclined at an angle to the vertical plane and placed in pairs opposite each 80 other on the sliding members 7. Said brushes are so placed as to form a V-shaped recess or pocket adapted to receive the fish or sardines from the chutes 5 and 6 respectively. The guide members 9 are tied together transversely by the cross pieces 9^a and are supported at their ends by the support 10, one of said supports also serving as a guide for the sliding members 7. The 85 brushes 8 are further mounted in pairs superimposed in staggered relation with each other, said upper brushes adapted to receive the sardines or fish from the upper chute 5 and the lower brushes adapted to receive the sardines or fish from the lower chute 6 inter- 90 95 mediate the said upper chutes. The slide members carrying the brushes above and below are connected on either side by the tie bars 11 respectively. Said tie bars are provided with bosses 11^a adapted to receive connecting rods 12 which are pivotally mounted 100 therein. The other ends of said connecting rods are revolvably mounted on the crank shaft 13 which is also revolvably mounted on the shaft supports 14. Said crank shaft is 105 driven by the pulley 15 secured to said shaft. It is obvious that by this means of operation there is imparted reciprocating motion to the slide members alternately with each other; that directly below and extending 110 beyond either end of said pairs of brushes there are provided downwardly extending,

gradually deepening, curved bottom chutes for receiving the sardines as they fall from the brushes head foremost, tending to keep the sardines with their heads in that course 5 and further to turn the sardines on their backs; that the center of gravity of a sardine is near its back so it naturally follows that the sardine will assume a position with the center of gravity at its lowest point if allowed to turn freely.

It is further obvious that as the sardines are brought from the storage tank or hopper over the conveyer they drop onto either the upper or lower chutes 5 and 6 respectively 15 and then onto the upper and lower brushes, since said brushes are reciprocably mounted alternately with each other and provided with comparatively sharp edges thereon and since the sardines are provided with scales 20 the blades of said brushes will engage the scales when moving forwardly on the sardine tending to move the sardines between the brushes head foremost into the chutes below.

25 In Fig. 4 of the drawings I have shown a modification of my apparatus with a chute 5 comparatively shorter and the chute 6 eliminated or reversed forming the guard 18 to deflect the sardines as they fall from 30 the conveyer onto the brushes which are off set and slightly below the upper brushes. The slide and guide members, the operating mechanism, and the chutes 16 and 17 are 35 similar to those described above.

35 Though I have shown and described a particular construction, combination and arrangement of parts and portions and a certain modification thereof I do not wish to be limited to this particular construction, 40 combination and arrangement nor to the modification but desire to include in the scope of my invention the construction, combination and arrangement substantially as set forth in the appended claims.

45 Having thus described my invention what I claim as new and desire to secure by Letters Patent is:

1. An apparatus of the class described, including brushes placed opposite each 50 other adapted to receive fish between said brushes and mounted to reciprocate alternately with each other, and means for reciprocating said brushes.

2. An apparatus of the class described, 55 including oppositely mounted horizontal brushes vertically inclined toward and reciprocating alternately with each other, means on said brushes adapted to alternately engage the outer edges of the scales 60 of fish moving the same head foremost in the direction of the engaging brushes toward the ends of said brushes.

3. An apparatus of the class described, 65 including parallel slide members adapted to reciprocate alternately with respect to

each other, a plurality of brushes secured opposite and in spaced relation with each other to each of said members, each pair of oppositely disposed brushes adapted to receive fish there between, adapted to alternately engage the outer edges of the scales of the fish, moving the same head foremost in the direction of the engaging brushes toward the end of the latter.

4. An apparatus of the class described, 75 including parallel slide members, means for reciprocating said members alternately with each other, a plurality of brushes secured opposite and in spaced relation with each other to each of said members, each pair of 80 oppositely disposed brushes inclined with each other adapted to receive fish there between, adapted to alternately engage the outer edges of the scales of the fish moving the same head foremost in the direction of the engaging brushes 85 toward the end of the latter.

5. An apparatus of the class described, 90 including parallel slide members, means for reciprocating said slide members alternately with each other, a plurality of brushes secured opposite and in spaced relation with each other to each of said members, each pair of oppositely disposed brushes inclined with each other adapted to receive fish there between, adapted to alternately engage the outer edges of the scales of the fish moving the same head foremost in the direction of the engaging brushes 95 toward the end of the latter, and a conveyer adapted to discharge fish from a supply means on to said brushes.

6. An apparatus of the class described, including parallel slide members, means for reciprocating said slide members alternately with each other, a plurality of brushes secured opposite and in spaced relation with each other to each of said members, each pair of oppositely disposed brushes inclined with each other adapted to receive fish there between, means on said brushes adapted to alternately engage the outer edges of the scales of the fish, moving the same head foremost in the direction of the engaging brushes toward the end of the latter, a conveyer adapted to discharge fish from a supply means on to said brushes and downwardly extending, gradually deepening curved bottom chutes directly below and extending in width beyond either end of said 115 pairs of oppositely disposed brushes.

7. An apparatus of the class described, including parallel slide members, means for reciprocating said members alternately with each other, a plurality of brushes secured 120 opposite and in spaced relation with each other to each of said members, each pair of oppositely disposed brushes inclined with each other adapted to receive fish there between, means on said brushes adapted to 125 receive fish there between, means on said brushes adapted to 130

alternately engage the outer edges of the scales of the fish, moving the same head foremost in the direction of the engaging brushes toward the end of the latter, chutes or
5 guards directing fish on to said brushes, a conveyer adapted to discharge fish from a supply means onto said chutes or against said guards, and downwardly extending,

gradually deepening curved bottom chutes directly below and extending in width beyond either end of said pairs of oppositely disposed brushes.

In testimony whereof, I have hereunto set my hand at San Diego, California this 27 day of January 1922.

FRANK HEATH.
